ELECTRON MULTIPLIER

Robert David Reilly, Fort Wayne, Ind., assignor,
by mesne assignments, to Farnsworth Research
Corporation, a corporation of Indiana

Application April 3, 1944, Serial No. 529,299

4 Claims. (Cl. 250—175)

1

This invention relates to electron multipliers and particularly to devices of this character employed with phototubes.

It is customary for numerous purposes to employ phototubes for the purpose of developing electrical energy in response to and in correspondence with received light energy. Despite substantial improvements made in the electron emissivity of such devices, the developed electrical energy generally is not of a sufficient magnitude to enable the employment thereof directly. It, consequently, is necessary to provide apparatus for use in conjunction with a phototube in order to amplify the magnitude of the developed electrical energy sufficiently to permit utilization thereof. A frequently employed amplifying apparatus is an electron multiplier, preferably one having a plurality of secondary electron emissive electrodes.

As is well known in the art, however, it is necessary to locate the first of a series of such multiplier electrodes adjacent to the photosensitive surface of the phototube cathode. Where the surface of the cathode is relatively small and is not required to intercept light from an appreciably wide angle, it is usual to locate the entrance opening of the first multiplier electrode adjacent to the peripheral edge of the cathode. Where the photosensitive surface of the cathode is of considerable area, however, such an arrangement is not completely satisfactory for the reason that a substantial portion of the cathode surface is too remote from the multiplier electrode to enable the acceleration of electrons emitted therefrom toward the multiplier electrode without employing abnormally high accelerating voltages between the cathode and the multiplier electrode.

Such a difficulty is overcome by the use of a centrally apertured cathode and a multiplier electrode disposed adjacent to the cathode aperture in the space contiguous to the photosensitive surface thereof. Such a structure forms the subject matter of a copending application of L. G. Wolfgang, Serial No. 537,953 filed May 29, 1944, and entitled "Photocell multiplier tube."

The structural arrangement disclosed in the copending Wolfgang application referred to is a substantial improvement over devices previously used. However, for some uses of phototube multipliers it has the disadvantage that the multiplier electrode is in a position to obstruct some light directed toward the phototube at an angle to the cathode surface. It sometimes is necessary to employ a phototube multiplier capable of responding to light received from any

2

source within a substantial angular zone with respect to the phototube. In order that such a device be capable of producing a maximum response to the received light it is necessary that the phototube multiplier be constructed so that none of the received light is prevented from reaching the photosensitive surface of the cathode.

It is an object of the present invention, therefore, to provide a phototube multiplier having a novel structural arrangement of the component electrodes, whereby substantially all of the light received from a zone angularly related to the device is utilized to actuate the device.

15 In accordance with the invention, there is provided a phototube device having a cathode in which is formed an aperture. An electrode which bears an anodic relationship to the cathode is disposed on the side of the cathode which is remote from the photosensitive surface thereof. This anodic electrode is provided with an auxiliary electron and light pervious electrode which is electrically connected thereto and which extends through the cathode aperture into the 20 space contiguous to the photosensitive surface of the cathode.

25 For a better understanding of the invention, together with other and further objects thereof, reference is had to the following description, 30 taken in connection with the accompanying drawing, and its scope will be pointed out in the appended claims.

The single figure of the drawing is a longitudinal cross sectional view of a phototube multiplier embodying one form of the invention.

35 Referring now to the drawing, the phototube multiplier is enclosed in an evacuated envelope 1. A cathode 2, having a concave photosensitive surface of considerable area is mounted in the 40 envelope in such a manner that the photosensitive surface is adjacent to and faces a transparent end wall of the envelope. The cathode is provided with a centrally disposed aperture 3. The electron multiplier used in conjunction with the 45 phototube comprises a plurality of conventional box-type electrodes, such as 4 and 5. Each of these electrodes has the interior surface thereof treated in a manner to render it capable of emitting multiplied numbers of secondary electrons upon impingement thereof by electrons derived from a preceding electrode. The multiplier electrodes are serially arranged in a conventional manner, as shown.

The first end one 4 of these multiplier electrodes is disposed with its entrance opening adja-

cent to the cathode aperture 3. This electrode also is provided with an auxiliary perforate electrode 6 which may be in the form of a screen or grid. The perforate electrode is pervious to both light and electrons, and extends through the cathode aperture into the space contiguous to the concave photosensitive surface of the cathode 2. It is electrically connected to the multiplier electrode 4 and may have substantially any desired shape, such as a substantially cylindrical configuration, as shown.

An electron collecting electrode 7 is located adjacent the exit opening of the other end one 5 of the plurality of multiplier electrodes. The collecting electrode may have any desired shape, such as the disk configuration shown.

The cathode, the multiplier electrode and the collecting electrode are connected electrically in a well known manner to a conventional source of energy (not shown). These connections are made through the press portion 8 of the tube envelope. If desired, the conductors extending through the tube press to the tube electrodes may be of relatively heavy gage wire so that they serve also as the supporting means for the electrodes. If desired, the cathode 2 may also be provided with a screen 9, which is electrically connected to and supported by the peripheral edge of the cathode.

Referring now to the operation of the phototube multiplier embodying the present invention, it is assumed that the usual voltages are impressed upon the tube electrodes. For example, the multiplier electrode 4 and its auxiliary perforate electrode 6 has applied thereto a voltage of the order of a hundred volts positive with respect to the cathode 2 and the collecting electrode. In like manner, the voltage of each of the succeeding multiplier electrodes and the collecting electrode is correspondingly more positive than the immediately preceding electrode. Thus, any one of these electrodes bears an anodic relationship to the cathode 2. By reason of the concave surface configuration of the cathode 2, the device is capable of receiving light in substantially equal quantities from all points within a relatively large zone angularly related to the tube. The incidence of light on the photosensitive surface of the cathode effects the emission of electrons from every unit area of the cathode in numbers corresponding to the quantity of light falling upon the respective areas. These emitted electrons have relatively low velocities. In order to effect the impingement of these electrons upon the first stage multiplier electrode, it is necessary to create an accelerating field of sufficient scope and strength to influence all of the electrons emitted from the cathode. Such a field is produced by the auxiliary perforate electrode 6. This electrode extends sufficiently within the space contiguous to the photosensitive surface of the cathode to attract electrons emitted from any portion of the cathode surface. The emitted electrons, therefore, are accelerated toward the perforate electrode and substantially all of them pass through the meshes or perforations of this electrode. Thence they are drawn toward the secondary electron emissive surface of the first stage multiplier electrode 4 upon which they impinge with sufficient velocity to effect the emission of increased numbers of secondary electrons.

The electron multiplication process through the succeeding stages of the multiplier is sufficiently well known to require no additional description thereof. The multiplied stream of elec-

trons ultimately is collected by the collecting electrode 7 to which may be connected any desired utilization circuit.

By reason of the novel structural arrangement of the phototube multiplier in accordance with this invention, there is produced a device which has large light gathering properties and one in which maximum utilization is made of the received light. The large surface area of the phototube cathode provides the device with large light gathering properties. The disposition of the electron multiplying apparatus on the side of the cathode remote from the photosensitive surface thereof insures that none of the incident light will be obstructed thereby. The provision of the perforate electrode 6 enables the use of substantially all of the photoelectrons emitted by the cathode. Also, by reason of its perforate configuration, it offers substantially no obstruction to light, despite the fact that it is located in the space contiguous to the photosensitive surface of the cathode.

While there has been described what, at present, is considered the preferred embodiment of the invention, it will be obvious to those skilled in the art that various changes and modifications may be made therein without departing from the invention, and therefore, it is aimed in the appended claims to cover all such changes and modifications as fall within the true spirit and scope of the invention.

What is claimed is:

1. A phototube multiplier comprising, a cathode having a concave photosensitive surface and a centrally disposed aperture formed therein, a secondary electron emissive multiplier electrode disposed on the side of said cathode remote from the photosensitive surface thereof adjacent to said cathode aperture, a perforate electrode electrically connected to said multiplier electrode and extending through said cathode aperture into the space contiguous to the photosensitive surface of said cathode, and an electron collecting electrode disposed in spaced relation to said multiplier electrode and adapted to receive electrons emitted under the control of said multiplier electrode.

2. A phototube multiplier comprising, a cathode having a concave photosensitive surface and a centrally disposed aperture formed therein, a box-type secondary electron emissive multiplier electrode disposed on the side of said cathode remote from the photosensitive surface thereof adjacent to said cathode aperture, a field producing screen electrically connected to said multiplier electrode and extending through said cathode aperture into the space contiguous to the photosensitive surface of said cathode, and an electron collecting electrode disposed in spaced relation to said multiplier electrode and adapted to receive electrons emitted under the control of said multiplier electrode.

3. A phototube multiplier comprising, a cathode having a concave photosensitive surface and a centrally disposed aperture formed therein, a plurality of secondary electron emissive multiplier electrodes serially arranged on the side of said cathode remote from the photosensitive surface thereof, first and second ones of said multiplier electrodes being disposed respectively at opposite ends of said serial arrangement, said first multiplier electrode being disposed adjacent to said cathode aperture, an auxiliary screen electrode electrically connected to said first multiplier electrode and extending through said

cathode aperture into the space contiguous to the photosensitive surface of said cathode, said screen electrode serving to produce a field for attracting cathode-emitted electrons toward said aperture, and an electron collecting electrode disposed adjacent to said second multiplier electrode and adapted to receive electrons therefrom.

4. A phototube multiplier comprising, a cathode having a concave photosensitive surface of considerable area and a centrally disposed aperture formed therein, a plurality of box-type secondary electron emissive multiplier electrodes serially arranged on the side of said cathode remote from the photosensitive surface thereof, first and second ones of said multiplier electrodes being disposed respectively at opposite ends of said serial arrangement, said first multiplier electrode being disposed adjacent to said cathode aperture, a substantially cylindrical screen electrically connected to said first multiplier electrode and extending through said cathode aperture into the space contiguous to the photosensitive surface of said cathode, said screen

serving to produce a field for accelerating cathode-emitted electrons toward said first multiplier electrode, and an electron collecting electrode disposed adjacent to said second multiplier electrode and adapted to receive electrons therefrom.
